[57] CLAIM

The ornamental design for a wall-mounted bicycle storage rack, as shown.

DESCRIPTION

FIG. 1 is a top, front perspective view of the wall-mounted bicycle storage rack showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a side elevational view thereof, the opposite side being a mirror image.

FIG. 1**FIG. 6****FIG. 4****FIG. 5**

FIG. 2**FIG. 3**
